WATCH BRACELET OR SIMILAR ARTICLE

Morris D. Gandelman, Fort Lee, N.J., assignor to Jacques Kreisler Manufacturing Corporation, North Bergen, N.J., a corporation of New Jersey

Filed May 24, 1963, Ser. No. 75,051

Term of patent 7 years

(Cl. D45—4)

The dominant features of my design reside in the portions shown in full lines.

I claim:

The ornamental design for a watch bracelet or similar article, substantially as shown and described.
